UNITED STATES PATENT OFFICE.

ARTHUR E. WELLS, OF TORONTO, ONTARIO, CANADA.

GRATING.

Application filed October 31, 1921. Serial No. 511,780.

The principal objects of this invention are to provide a grating for covering open spaces in which the bars are very rigidly connected together, thus rendering it very safe for traffic thereon, and to devise a construction which will be extremely strong and which by reason of its extreme simplicity may be manufactured at very low cost.

A further object is to devise a grating presenting a surface which will minimize the possibility of slipping.

The principal feature of the invention consists in the arrangement of notched transverse bars in which the parallel longitudinal bars are secured by deforming the metal of the bars after they have been placed together.

In the drawings, Figure 1 is a perspective view of a portion of a grating constructed in accordance with this invention.

Figure 2 is an underside plan view.

Figure 3 is a section through the line 3—3 of Figure 2.

Figure 4 is an enlarged sectional detail through the apex of a portion of one of the V bars showing the interlocking of the members effected by the dual deformation of the bars.

Steel gratings are being utilized to a rapidly increasing extent for covering open areas in pavements and it is necessary to provide a very strong and durable structure to withstand the traffic.

In the construction herein shown the cross bars 1 which are preferably the shorter bars of the grating, are formed of a substantially V-shaped section being made of angle steel having the flanges bent inwardly. These bars are formed with notches 2 cut in the angle being preferably punched transversely.

Longitudinal bars 3 are laid in the notches 2 which are slightly deeper than the depth of the bars 3. The composite structure is then subjected to the action of a press, suitable punches being arranged to engage the underside of the bars 3 between the flanges of the cross bars 1 to deform the metal of the longitudinal bars, spreading the metal laterally to engage the under surface of the bars 3. This deformation is preferably formed by double punches so that the curved lips 4 spread out from both sides of the bars to engage the inner apexes of the cross bars and effecting a lateral displacement of a portion of the side walls of the notches adjacent the inner apex of the cross bars.

Simultaneous with this punching operation it is desirable to slightly deform the metal of the cross bars on the upper side. This is done by suitable projections on the bed 60 plate of the press which form the notches 5 in the top edge of the cross bars 1, pressing the metal at the notches slightly over the longitudinal bars and effecting a downward displacement of the upper portions of the 65 side walls relative to the bars 3 with the result that a jamming action is produced between the outwardly displaced portion of the longitudinal bars 3 and the walls of the notches 2, the intermediate portion of the 70 apex between the downwardly displaced side wall portion being supported from below during such displacement.

As is shown in the drawings, it is not necessary to deform the longitudinal bars 75 and the cross bars at every intersection, the drawing showing them deformed at alternating intersections.

Gratings thus constructed may be put together in a very rapid manner, gang punches 80 being used to cover a large area with one operation of the press. No riveting, drilling or fitting of bolts or other fasteners are required and the structure when completed is extremely rigid and strong.

The longitudinal bars are spaced apart whatever distance desired but even though very closely arranged they present an excellent non-slipping surface and the angle edges of the cross bars which preferably 90 project slightly above the longitudinal bars, present a very excellent obstruction to longitudinal slipping.

What I claim as my invention is:—

1. A plurality of horizontally arranged 95 V-shaped angle bars (1) parallelly spaced and disposed with their apexes upward and each having a plurality of notches (2) with horizontal bottoms formed in the apex, a plurality of horizontally arranged cross bars 100 (3) inserted in said notches and having flat bottom surfaces resting flatly on the horizontal bottoms of said notches, the upper surfaces of the latter bars being arranged in a common plane slightly below the uppermost edges of said V bars (1), said latter bars 3 being deformed laterally at (4) to engage the underside of the metal forming the apexes of the V bars.

2. A plurality of horizontally arranged 110 V-shaped bars parallelly spaced and disposed with their apexes upward and each having

a plurality of notches with horizontal bottoms formed in the apex, a plurality of horizontally arranged cross bars of rectangular cross section inserted in said notches and having their flat bottom surfaces resting flatly on the horizontal bottoms of said notches, the upper surfaces of the latter bars being arranged in a common plane slightly below the uppermost edges of said V bars, said lat-

ter bars being deformed laterally and forced upwardly on either side of the notches in the V bars to solidly engage the underside of the apexes of said V bars, and said V bars being deformed laterally at the sides of said notches to press the metal of the V bars into intimate contact with the deformed under portions and the side walls of the cross bars.

ARTHUR E. WELLS.
